CLAIM

The ornamental design for a animal saving escape ramp, as shown and as described.

DESCRIPTION

FIG. 1 is a front view showing my new design.

FIG. 2 is a rear view thereof.

FIG. 3 is a left end view thereof.

FIG. 4 is a right end view thereof.

FIG. 5 is a top view thereof.

FIG. 6 is a bottom view thereof.

FIG. 7 is a front perspective view thereof.

FIG. 8 is a rear perspective view thereof.

FIG. 9 is an exploded front perspective view thereof, illustrating the floater bar detached from the base and bent in U shape for fitting two ends of the floater bar in the two end holders and a middle portion of the floater bar held by the ring shape holder provided on the base.

FIG. 10 is an exploded rear perspective view of FIG. 9; and, FIG. 11 is an exploded front perspective view thereof, illustrating the detached floater bar in elongated shape before bending to U shape.
